UNITED STATES PATENT OFFICE.

WILL B. BROWN, OF GOSHEN, INDIANA.

LIGHT-FIXTURE.

No. 827,783.

Specification of Letters Patent.

Patented Aug. 7, 1906.

Application filed August 28, 1905. Serial No. 276,050.

To all whom it may concern:

Be it known that I, WILL B. BROWN, a citizen of the United States, residing at Goshen, in the county of Elkhart and State of Indiana, have invented a new and useful Improvement in Light-Fixtures, of which the following is a specification.

My invention relates particularly to such fixtures as chandeliers, brackets, &c., adapted for use either as electric or as combination fixtures; and my primary object is to provide a thoroughly practicable, cheap, and highly-ornamental wooden fixture which may be readily designed to harmonize with the character of the finish and furnishings of the room in which it is to be installed. Thus, for instance, the fixtures illustrated in the accompanying drawings harmonize with mission furniture and antique or weathered-oak trimmings.

The preferred construction is illustrated in the drawings, in which—

Figure 1 represents a broken vertical sectional view of a wooden chandelier constructed in accordance with my invention; Fig. 2, a view, partly in section and partly in elevation, of a bracket-fixture constructed in accordance with my invention; Fig. 3, a plan view of a pipe-suspending spider or ceiling-plate; Fig. 4, a broken section showing a detail of the connection between the members of a combination lamp-socket box and shade-base employed; Fig. 5, a broken plan section taken as indicated at line 5 of Fig. 1; Fig. 6, a plan view of the lower member of said shade-base; Fig. 7, a bottom plan view of the upper member of said shade-base; Fig. 8, an inner face view of a block or union employed for connecting said shade-base to the bracket-arm of the chandelier, and Fig. 9 a section taken as indicated at line 9 of Fig. 5.

Referring now to Figs. 1 and 3 to 9, inclusive, A represents the vertical hollow shaft or stem of a chandelier; B, means for connecting the same with a ceiling B'; C, a hollow bracket-arm support suspended by the shaft A; D, bracket-arms connected with the member C; E, combination lamp-socket boxes and shade-supports suspended from the extremities of the arms D; F, lamp-sockets incased therein and fitted with lamps F', and G shades or globes depending from the members E. The shaft A comprises a tubular metallic inner member a of circular cross-section and a tubular wooden outer member a', which preferably is of square cross-section.

The ceiling-attaching means B comprises a spider b, having an upper ring b', joined by screws b² to the ceiling, and a lower ring b³, into which the upper end of the tube a is screwed, and a stepped inverted wooden pyramid b⁴ of square wooden blocks glued together, the pyramid having a central opening b⁵, accommodating the spider b and shaft A. The larger or base block of the pyramid-forming blocks is joined by screws b⁶ to the ceiling. The box-form bracket-arm support C is of wood and comprises an open-ended tubular wooden member c of square cross-section, a top plate c', whose edges project beyond the outer surfaces of the member c and which is joined by screws c² to the top of the member c, and a bottom member c³, having a square tenon c⁴, fitting with the lower end of the member c and joined thereto by screws c⁵. Upon the top c' rests a square-shaped block c⁶. The lower end of the member a' is tenoned to pass through openings in the members c' c⁶, and the tube a projects beneath the member c' and is equipped with a nut c⁷, which serves to clamp the members c' c⁶ between itself and the shoulder at the base of the tenon. The arms D comprise wooden members d of square cross-section and having bores d' lined with a non-conducting coating d², Fig. 9. The ends are provided with circular tenons d³ d⁴. The tenons d³ pass through perforate rectangular blocks d⁵ and enter perforations in the walls of the member c. The tenons d⁴ enter mortises d⁶, Fig. 8, in the inner faces of blocks or unions d⁷. The blocks d⁷ are provided at their lower ends with tenons d⁸, through which extend passages d⁹, communicating with the bores d' of the members d. Each combination socket-box and shade-base E is of wood and comprises a lower rectangular horizontal block e, Figs. 1, 4, and 6, having a vertical central bore e', screw-perforations e², and a transverse groove e³ on the upper surface of the block and intersecting the bore e', and an upper pyramidal block e⁴, mortised at its upper end to receive the corresponding tenon d⁸, and chambered beneath its mortise to receive the upper end of the lamp-socket F. The blocks are joined by screws e⁵, Fig. 4, which extend through the block e and into perforations e⁶ in the block e⁴. The lamp-sockets F have connected therewith the usual circuit-changing keys f, which extend through the grooves e³ in the blocks e. Each shade or globe G comprises an open-ended

pyramidal hollow wooden frame g , whose inclined faces g' have openings receiving glass or other transparent material g^2 . The upper end of the frame is joined by dowels g^3 to the 5 lower side of the block e .

Referring to Fig. 2, D' represents a bracket-arm, E' a combination lamp-socket box and shade-base, and G' a shade supported from the member E' . The construction of and 10 connections between the parts is the same as described with reference to the chandelier-arms D , except that the arm D' has a tenoned extremity which fits into a mortise in a stepped wooden plate h , which is removably 15 secured to a vertical wall h' by screws h^2 . The wall h' is represented as a part of a bracket-support C' , similar to the support C . However, the plate h may be attached to the vertical wall of a room, as is evident. The 20 bracket-arm D' is valuable in chandelier connection, inasmuch as it enables the fixture to be shipped in a "knocked-down" condition, the assembling being readily accomplished by the dealer. All the passages except the 25 one having the metallic walls preferably have their walls lined by a coating of non-conducting material d^2 , as indicated by the heavy internal lines. Vertical wires k extend through the supporting-pipe a from the ceiling, and 30 joined to these wires within the chamber c are wires k' , which pass through the chandelier-arms and are joined to the lamps within the lamp-socket boxes. The construction provides for the convenient wiring of the fixtures. Thus the lower cap-piece c^3 of the 35 chamber c is removable to enable the wires k and k' to be connected, and the members e and e^4 are separable to enable the lamp-socket to be inserted and properly connected. So, 40 also, the nut b^7 may be applied before the cap-piece c^3 is secured in place. The construction is thoroughly adapted to its purpose, and its value will at once be appreciated by those skilled in the art of the production of 45 artistic fixtures.

Changes in details of construction within

the spirit of my invention may be made. Hence no undue limitation should be understood from the foregoing detailed description.

What I regard as new, and desire to secure 50 by Letters Patent, is—

1. In a fixture of the character set forth, the combination of a hollow arm, and a sectionally-constructed lamp-socket box supported on said arm and provided with a lateral key-passage, for the purpose set forth. 55

2. In a fixture of the character set forth the combination of a hollow arm equipped at an extremity with a union, and a lamp-socket box connected with said union, comprising 60 an upper chambered member and a lower chambered member removably connected with said upper member, one of said chambered members having a lateral key-passage, for the purpose set forth.

3. In a fixture of the character set forth, the combination of a hollow arm, a union carried by an extremity of said arm, and a lamp-socket box comprising a chambered upper block supported from said union, and a removable lower block having a vertical bore and provided at its upper portion with a lateral groove affording a key-passage, for the 70 purpose set forth.

4. In a fixture of the character set forth, 75 the combination with a hollow arm, of a sectionally-constructed lamp-socket box connected therewith and a shade-frame suspended from and detachably connected with said box, for the purpose set forth. 80

5. In a fixture of the character set forth, the combination of a wooden lamp-socket box having separable upper and lower sections, one of said sections having a lateral key-passage, and a wooden frame suspended from 85 the lower section and having rigid connection therewith, for the purpose set forth.

WILL B. BROWN.

In presence of—

F. M. WIRTZ,
J. H. LANDES.
